PORTABLE RANGE OR SIMILAR ARTICLE

Terry J. Simpkins, Columbus, Ohio, assignor to Trak Incorporated, Columbus, Ohio, a corporation of Ohio

Filed Apr. 25, 1963, Ser. No. 74,606

Term of patent 7 years

(Cl. D81—10)

The dominant features of my design reside in the portions shown in full lines.

I claim:

The ornamental design for a portable range or similar article, substantially as shown and described.
